Primary Examiner—Ralf Seifert

(74) Attorney, Agent, or Firm—Sarah J. Rhoades, Esq.

(57) **CLAIM**

The ornamental design for the surface ornamentation for an article of manufacture, as shown and described.

DESCRIPTION

FIG. 1 is an elevational view of the ornamental surface design generically described as “inhalation hazard” showing the new design for use on articles of manufacture.

1 Claim, 1 Drawing Sheet
